UNITED STATES PATENT OFFICE.

WILFORD J. HAWKINS, OF BROOKLYN, NEW YORK, ASSIGNOR TO AMERICAN MACHINE AND FOUNDRY COMPANY, A CORPORATION OF NEW JERSEY.

CARBURETING APPARATUS.

Application filed February 29, 1924. Serial No. 695,908.

To all whom it may concern:

Be it known that I, WILFORD J. HAWKINS, a citizen of the United States, residing at Brooklyn, county of Kings, and State of New York, have invented a new and useful Improvement in Carbureting Apparatus, of which the following is a specification.

This invention relating to a carbureting apparatus which is particularly adapted for use in oil burning systems. It is, however, capable of use for other purposes. The main object of the invention is the production of a simplified carbureting apparatus that is inexpensive to build and install, automatic in action, compact, highly efficient, and inexpensive to maintain in operation. With this and other objects not specifically mentioned in view, the invention consists in certain constructions and combinations which will be hereinafter fully described and then specifically set forth in the claims hereunto appended.

In the accompanying drawings, which form a part of this specification and in which like characters of reference indicate the same or like parts, Fig. 1 is a central sectional view of an apparatus constructed in accordance with the invention; Fig. 2 is a fragmentary sectional view taken in a plane which includes the oil inflow valve 19; and Fig. 3 is an enlarged detail view of the venturi and needle valve shown in Fig. 1.

In carrying the invention into effect, there is provided a source of fuel oil supply. There is further provided a carburetor receiving oil from said source, and air from the atmosphere, and mixing the two. And there is further provided a pump actuating said carburetor and receiving the air and oil mixture therefrom and delivering it under pressure. When the apparatus is used in an oil burning system, there is further provided a burner, receiving the mixture under pressure from the pump; and means for igniting the mixture. When the source of fuel oil supply is buried in the ground, or otherwise located at a level lower than that of the carburetor, the said source of supply includes a vacuum tank connected with the main supply tank, and means actuated by the pump for producing the necessary vacuum. And means are provided for varying the pressure and quantity of the delivered mixture. All of the

above mentioned parts and means may be widely varied in construction within the scope of the claims, for the particular apparatus selected to illustrate the invention is but one of many possible concrete embodiments of the same. The invention therefore is not to be restricted to the precise details of the structure shown and described.

The drawings illustrate an embodiment of the invention adapted for use as an oil burner; and in this embodiment there is provided a source of fuel oil supply including a supply tank 4 of any suitable construction and capacity. This supply tank 4 is connected, by means of a pipe 5, with a vacuum tank 6, of the well known Stewart type and located at a higher level. There is also provided a carburetor indicated generally by the reference character 7, and, as shown, this carburetor is inbuilt with a pump 8 which is of the high-speed rotary type and directly driven by an electric motor not shown. The carburetor has a float chamber 9 in which is located a float 10 having upwardly projecting lugs 11 (only one being shown) pivoted to arms 13 and 14, both fulcrumed on a pin 15, carried by a depending lug 16, formed on a cover 17, which closes the upper end of the float chamber 9. It may be here remarked that this cover 17 removably supports all of the movable carburetor parts within the float chamber 9. The free ends of the arms 13 and 14 have a slot and pin engagement 18 with a valve 19 adapted to control the gravity flow of oil through a pipe 20 from the vacuum tank 6 to the float chamber 9. It will be readily understood that the valve will close when the float rises, and will open when the float falls.

A conduit 21 leads from the upper part of the float chamber 9 to the pump 8 on the suction side of the latter at 22. The upper end of the conduit 21 terminates in the stationary part of a venturi 23 located within the float chamber 9. Coacting with the stationary part of the venturi is an adjusting tube 24. This tube is threaded at 25 through the top of the cover 17. It may be adjusted vertically in order to vary the form and size of the air passage in the venturi 23. It is held in adjusted position by means of a lock nut 26 of well known construction and operation. Threaded into the

upper part of the tube 24 is a needle valve 27 which is adjustable in the tube by means of the thread. It is locked in adjusted position by means of a lock nut 28. The operating end of the needle valve 27 engages a bush 29, driven into the bore of the tube 24. Just above the top of the bush 29 small holes 30 are drilled from the bore of the tube 24 to the interior of the venturi 23.

5 The lower part of the tube 24 is open and is submerged in the fuel oil in the float chamber.

10 The lower part of the tube 24 is open and is submerged in the fuel oil in the float chamber.

The carburetor is provided with a restricted air intake 31 in open communication with the atmosphere and with the interior of the float chamber 9. A suction pipe 32 is in communication with the vacuum tank 6 and with the conduit 21; and this pipe is provided with a valve 33 for controlling its effective action.

20 A conduit 34 leads from the pressure side of the pump 8, to and through the cover 17, to establish connection with a pipe 35 leading to a burner 36. This burner 36 is provided with a screen 37 to prevent backfire, and it has a small delivery orifice 38. Just beyond the burner 36 is located an incandescent ignition device indicated diagrammatically at 39.

30 For the purpose of varying the pressure of the delivered mixture and controlling the quantity of oil used during any given time interval, there is provided a by-pass pipe 40 having therein a valve 41. One end of this by-pass pipe is open to the suction pipe 32; the other is open to the delivery pipe 35; the valve controls its action.

The operation of the apparatus is as follows: When the pump is started, air is drawn from the float chamber 9, through the venturi 23 and conduit 21, to the pump which discharges it into the conduit 34. Air then flows into the float chamber 9 through the intake 31. If there is no vacuum in the 40 vacuum tank 6 when the pump is started, the air flowing into the float chamber comes in part from the atmosphere through the intake 31 and in part from the vacuum tank through the pipe connection 32. After a 45 vacuum is established in the vacuum tank 6, however, all the air will come through the intake 31. The needle valve 27 and adjustable Venturi tube 24 being properly set, and the lower ends of the tube 24 being submerged in the oil in the float chamber, the 50 passage of air through the venturi 23 picks up atomized oil in the usual manner, and the mixture is drawn down through the conduit 21. The restricted orifice of the burner 36 causes pressure of the mixture to build up in the conduit 34 and pipe 35. At the proper time the ignition device is switched on, and the mixture issuing from the orifice 38 is thereby ignited. It will be readily understood that when a vacuum is established in

the vacuum tank 6, oil will flow from the supply tank 4, through the pipe 5, to the vacuum tank 6; and that thereafter the vacuum tank float will automatically control the oil flow in the usual manner. So long as fuel oil is available in the supply tank 4, therefore, the apparatus will operate automatically. The location of all of the moving parts within the pump and carburetor housing, where they work in an oil mixture, 75 makes the whole apparatus self-lubricating. When it is desired to lower the pressure of the mixture to lessen the quantity delivered, the valve 41 is opened slightly. The partial vacuum in the suction pipe 32 and the pressure of the mixture in the pipe 35 then cause to set up a circulation, through the by-pass and pump, of a part of the delivered mixture; and this lowers its pressure and reduces the quantity delivered in any given 85 time interval.

What is claimed is:—

1. A carbureting apparatus comprising a source of fuel supply including a vacuum tank, a carburetor receiving oil from said source, and a pump actuating said tank and said carburetor and receiving mixture therefrom and delivering it under pressure. 90

2. A carbureting apparatus comprising a source of fuel oil supply including a vacuum tank, a carburetor receiving oil from said source, and a pump actuating said tank and said carburetor and receiving mixture therefrom and delivering it under pressure, and a burner receiving said mixture under pressure. 95

3. A carbureting apparatus comprising a source of fuel oil supply including a vacuum tank, a carburetor receiving oil from said source, and a pump actuating said tank and said carburetor and receiving mixture therefrom and delivering it under pressure, a burner receiving said mixture under pressure, and means for igniting said mixture. 105

4. A carbureting apparatus comprising a source of fuel oil supply including a vacuum tank, a carburetor receiving oil from said source, and a pump actuating said tank and said carburetor and receiving mixture therefrom and delivering it under pressure, a burner receiving said mixture under pressure, and means for preventing backfire. 110

5. A carbureting apparatus comprising a source of fuel oil supply including a vacuum tank, a carburetor receiving oil from said source, and a pump actuating said tank and said carburetor and receiving mixture therefrom and delivering it under pressure, said source including a supply tank and a vacuum tank connected therewith and means actuated by said pump for operating said vacuum tank. 120

6. A carbureting apparatus comprising 130

- a source of fuel oil supply including a vacuum tank, a carburetor receiving oil from said source, and a pump actuating said tank and said carburetor and receiving mixture therefrom and delivering it under pressure, said source including a supply tank and a vacuum tank connected therewith and valve controlled connections actuated by said pump for operating said 10 vacuum tank.
7. A carbureting apparatus comprising a source of fuel oil supply including a vacuum tank, a carburetor receiving oil from said source, and a pump actuating said tank and said carburetor and receiving mixture therefrom and delivering it under pressure, said carburetor being 15 built with said pump.
8. A carbureting apparatus comprising a source of fuel oil supply including a vacuum tank, a carburetor receiving oil from said source, and a pump actuating said tank and said carburetor and receiving mixture therefrom and delivering it under 20 pressure, said carburetor having means for maintaining a substantially constant supply of oil therein.
9. A carbureting apparatus comprising a source of fuel oil supply including a vacuum tank, a carburetor receiving oil from said source, and a pump actuating said tank and said carburetor and receiving mixture therefrom and delivering it under 25 pressure, said carburetor having a float chamber and a venturi therein.
10. A carbureting apparatus comprising a source of fuel oil supply including a vacuum tank, a carburetor receiving oil from said source, and a pump actuating said tank and said carburetor and receiving mixture therefrom and delivering it under 30 pressure, said carburetor having a float chamber and an adjustable venturi therein.
11. A carbureting apparatus comprising a source of fuel oil supply including a vacuum tank, a carbureter receiving oil from said source, and a pump actuating said tank and said carburetor and receiving mixture therefrom and delivering it under 35 pressure, said carburetor having a float chamber and an adjustable venturi therein and an adjustable needle valve coacting with said venturi.
12. A carbureting apparatus comprising a source of fuel oil supply including a vacuum tank, a carburetor receiving oil from said source, and a pump actuating 40
- said tank and said carburetor and receiving mixture therefrom and delivering it under pressure, said pump being of the high-speed rotary type. 60
13. A carbureting apparatus comprising a source of fuel oil supply including a vacuum tank, a carburetor receiving oil from said source, and a pump actuating said tank and said carburetor and receiving mixture therefrom and delivering it under pressure, a burner receiving said mixture under pressure, and an incandescent ignition device. 65
14. A carbureting apparatus comprising a source of fuel oil supply including a vacuum tank, a carburetor receiving oil from said source, and a pump actuating said tank and said carburetor and receiving mixture therefrom and delivering it under pressure, and a housing for said pump and carburetor forming a float chamber for the latter and having a cover 70 removably supporting all the parts of the carburetor within said chamber. 75
15. A carbureting apparatus comprising a source of fuel oil supply including a vacuum tank, a carburetor receiving oil from said source, and a pump actuating said tank and said carburetor and receiving mixture therefrom and delivering it under pressure, and a housing for said pump and carburetor forming a float chamber for the latter above said pump and having a cover removably supporting all the parts of said carburetor within said chamber and also having a conduit leading from the upper part of 80 said chamber to said pump. 85
16. A carbureting apparatus comprising a source of fuel oil supply including a vacuum tank, a carburetor receiving oil from said source, and a pump actuating said tank and said carburetor and receiving mixture therefrom and delivering it under 90 pressure, and means for varying the pressure of the delivered mixture. 95
17. A carbureting apparatus comprising a source of fuel oil supply including a vacuum tank, a carbureter receiving oil from said source, and a pump actuating said tank and said carburetor and receiving mixture therefrom and delivering it under pressure, and a valve-controlled by-pass for varying the pressure of the delivered mixture. 105
- In testimony whereof, I have signed my name, to this specification.
- WILFORD J. HAWKINS.
